UNITED STATES PATENT OFFICE.

PATRICK A. LEONARD, MICHAEL F. MALONEY, AND ERNEST FANDRICH, OF SCHENECTADY, NEW YORK.

FLUID-PRESSURE APPARATUS FOR BURNING POWDERED FUEL.

1,388,454.

Specification of Letters Patent. Patented Apr. 27, 1920.

Application filed August 16, 1919. Serial No. 317,979.

To all whom it may concern:

Be it known that we, PATRICK A. LEONARD, MICHAEL F. MALONEY, and ERNEST FANDRICH, all of Schenectady, in the county 5 of Schenectady and State of New York, have invented a certain new and useful Improvement in Fluid-Pressure Apparatus for Burning Powdered Fuel, of which improvement the following is a specification.

10 In Letters Patent of the United States No. 1,305,726, granted and issued to us under date of June 3, 1919, for an improvement in apparatus of the type above stated, we have set forth means for overcoming the 15 objections which obtain in appliances theretofore proposed and experimented with, in the particulars of conveying, injecting, and burning powdered fuel; for rendering the manner of using it absolutely free and safe 20 from explosion; for simplifying and cheapening the application of powdered fuel; and for rendering its use adaptable in all types of furnaces, whether operated for heating or melting metals, or in connection 25 with stationary, locomotive, or marine steam boilers.

Our present invention is based upon the same general operative principle as that of our Letters Patent No. 1,305,726 aforesaid, 30 and its object is to render its application more effective, particularly in furnaces of comparatively large dimensions.

The improvement claimed is hereinafter fully set forth.

35 In the accompanying drawings: Figure 1 is a vertical longitudinal central section through a reverberatory furnace provided with a combustion chamber, and a steam boiler heated thereby, illustrating an application of our invention; Fig. 2, a transverse section through the same, approximately on the line 2—2 of Fig. 1; Fig. 3, a partial horizontal section; and, Fig. 4, a vertical longitudinal section, on an enlarged scale, 45 through the outer portion of the fuel hopper and the fuel injector.

The type of furnace disclosed in our Letters Patent No. 1,305,726 aforesaid, is the ordinary form of metallurgical furnace, for 50 heating iron and steel used in making forgings, consisting of an inclosed heating chamber, having a single opening, controlled by a sliding door, and communicating with the atmosphere, and with a discharge flue or 55 stack, the heating chamber being provided

with two twyers, located, in line axially, on its opposite sides. One of said twyers discharges a jet of commingled powdered fuel and air under pressure, into the heating chamber, said jet impinging against a 60 jet of air under pressure, only, which is discharged from the opposite twyer, any additional supply of air, requisite to support combustion, being inducted through the bottom of the opening underneath the 65 door, which is always partially open during operation, and the products of combustion making their exit to the stack, in the opposite direction, through the upper part of same opening below the door. This type of 70 furnace has a single opening for the ingress of additional air supply and for the egress of the products of combustion.

In furnaces of the type to which our present invention relates, which are provided with a combustion chamber, and in the operation of which, when the escaping gases of combustion are utilized for the purpose of generating steam, the egress of the products of combustion is retarded by 75 constriction of the heating surface passages of the superimposed steam boiler, it becomes necessary to introduce the additional supply of air to support the combustion of the fuel, into the combustion chamber, in proportionate quantity to the amount of fuel 80 to be consumed, and also under sufficient pressure to overcome the resistance created by the greater length of traverse and restricted passages, so as to cause the heat 85 generated by combustion to travel through the furnace at the proper velocity to meet the operative requirements.

To this end, under our present invention, we apply to the sides of the combustion 95 chamber, one or more pairs (preferably a plurality) of twyers, the members of each pair being disposed in line axially, one twyer of each pair discharging a jet of commingled powdered fuel and air into the 100 combustion chamber, and the opposite twyer discharging a jet of air under pressure, only. When a plurality of pairs of twyers is applied, the fuel and air twyers, and the air twyers, of the several pairs, are alternated longitudinally in the combustion chamber to promote uniformity of action. The additional or supplemental air blast, 105 for supporting combustion and regulating the flow of the heat and gases throughout 110

the furnace, as well as for facilitating their flow through the heating passages of the boiler, when applied in connection with the furnace, is supplied through a pipe leading 5 to a twyer at the end of the combustion chamber of the furnace, and is delivered at an angle, preferably a right angle, to the axial lines of the jets from the side tuyers.

Referring descriptively to the specific embodiment of our invention illustrated in the drawings, and employing the term "furnace", as designating, generically, any receptacle for the consumption of fuel, whether a metallurgical furnace, boiler furnace, or boiler firebox, our invention is exemplified as applied in connection with a reverberatory furnace, 11, which, in and of itself, is of the ordinary form, inclosing a heating chamber, 1, and communicating 10 with a combustion chamber, 1^c, and provided with a discharge flue, 1^c, through which the waste gases pass to and through a flue, 8^a, surrounding the lower portion of a steam boiler, 8, and thence, through the tubes, 8^b, 15 of the boiler, to a stack, 1^d.

One or more pairs of tuyers, 2, 2, two pairs being, in this instance, illustrated, are fitted in opposite openings in the side walls of the furnace chamber, 1, said tuyers being 20 in line axially, and located in a horizontal plane, so that the currents discharged therefrom into the furnace chamber shall impinge directly one against the other. A supplemental or supporting blast twyer, 2^a, 25 is fitted in the end wall of the furnace chamber, in this instance in the same axial plane as, and at a right angle to, the side tuyers, 2, 2, so that the current discharged into the furnace chamber from the twyer, 2^a, impinges upon the currents discharged from the tuyers, 2, 2, in the same horizontal plane. Air blast pipes, 3, 3, lead from a source of air under pressure, into the side tuyers, 2, 2, and a blast pipe, 3^a, leads the 40 supporting column of air into the twyer, 2^a, the volume of air transmitted through said pipes being independently controlled by suitable blast gates of the ordinary construction.

50 A fuel hopper, 4, is located in any convenient position relatively to the furnace, and is connected by one or more suction pipes, 4^a, opening into it near its bottom, with one or more fuel injectors, 5, of the 55 Giffard type, the combining tube, 5^a, of each of which may be either connected directly with one of the blast pipes, 3, as indicated in the drawings, and most clearly shown in Fig. 4, or communicate with the 60 twyer, 2, into which said blast pipe leads, through an independent fuel delivery pipe, as preferred. Communication between the fuel hopper and each of the injectors is controlled by a suitable fuel regulating valve, 65 4^b, fitted in the suction pipe, 4^a, carrying an

arm, 4^c, actuated by an operating rod, 4^d, which extends to a location within convenient reach of the furnace operator. The fuel injector does not, in and of itself, form part of our present invention, and any suitable and preferred construction thereof may be applied, one of which is exemplified in our Letters Patent No. 1,305,726 aforesaid.

In cases where, as in the instance exemplified, a plurality of pairs of tuyers is applied, the opposite members of each pair are, as shown, alternated in position longitudinally in the combustion chamber, that is to say, the fuel and air tuyers, and the air tuyers, respectively, of each pair, are 70 located on alternately opposite sides of the combustion chamber, in order to promote uniformity of action of the opposing jets throughout the length of said chamber.

While we have specified air as the blast 85 medium utilized, our invention is not limited to the application thereof, as dry steam or other gas under pressure may be employed.

In the operation of an apparatus for burning powdered fuel, of the construction substantially as above described, a jet of powdered fuel, combined with a proportionate supply of oxygen contained in the air under pressure which is mingled with said jet, impinges directly against a properly proportioned, and oppositely directed, jet of oxygen, contained in air under pressure, said jets being discharged from the two axially coinciding tuyers, 2, 2, of each pair, on the 90 opposite sides of the furnace. Coincidently with the meeting of the jets of mingled fuel and air, and of air, respectively, from the side tuyers, 2, 2, they are encountered by a supplemental or supporting blast of 105 air, discharged from the end twyer, 2^a, the direction of which is toward the discharge end of the furnace chamber. As a result, the particles of fuel are thoroughly commingled with the oxygen of the air, and are 110 held in perfect suspension within the furnace, until entirely consumed, the traverse of the products of combustion being effected with minimum resistance. The discharge of the waste products is materially promoted 115 by the volume and direction of the supplemental or supporting air blast, and the independent regulation of the volumes of fuel and air supply, enables the proper relation of the functions of delivering the fuel, holding its particles in suspension, and affording it the proper supply of oxygen for combustion, to be maintained under the varying conditions of the operation of the furnace.

It will be obvious that our invention is 120 equally applicable, without variation of structural or operative principle, either in connection with metallurgical heating furnaces, the discharge gases of which are utilized for heating steam boilers, or to fur- 125

naces for generating steam only, without operation in metallurgical operations.

We claim as our invention and desire to secure by Letters Patent:

5. 1. The combination, with a furnace, of means for forcing thereinto a jet of commingled powdered fuel and air; means for delivering a jet of air under pressure into the furnace, in line with, and unobstructed from direct impingement against, said first specified jet; and means for delivering a volume of air under pressure into the furnace, at an angle to the common axial line of said two first specified jets.
10. 2. The combination, with a furnace, of two blast pipes, opening, in line axially, thereinto, on opposite sides of its middle plane, and unobstructed intermediately; means for forcing commingled powdered fuel and air into one of said pipes; means for forcing air under pressure into the other pipe; and an air blast pipe opening into the furnace, at an angle to said two first specified blast pipes.
15. 3. The combination, with a furnace, of two blast pipes, opening, in line axially, thereinto, on opposite sides of its middle plane, and unobstructed intermediately; means for forcing commingled powdered fuel and air into one of said pipes; means for forcing air under pressure into the other pipe; an air blast pipe opening into the furnace, at an angle to said two first specified blast pipes; and means for independently controlling each of said blast pipes.
20. 4. The combination, with a furnace, of two blast pipes, opening, in line axially, thereinto, on opposite sides of its middle plane, and unobstructed intermediately; a connection from the combining tube leading out of the injector, to one of said blast pipes; and an air blast pipe opening into the furnace, at an angle to said two first specified blast pipes.
25. 5. The combination, with a furnace, of a plurality of pairs of blast pipes, the members of each pair opening, in line axially, thereinto, on opposite sides of its middle plane, and unobstructed intermediately; means for forcing commingled powdered fuel and air into one pipe of each pair; means for forcing air under pressure into the other pipe of said pair; and an air blast pipe opening into the furnace at an angle to the axes of said pairs of blast pipes.
30. 6. The combination, with a furnace, of a plurality of pairs of blast pipes, the members of each pair opening, in line axially, thereinto, on opposite sides of its middle plane, and unobstructed intermediately; means for forcing commingled powdered fuel and air into a pipe of one pair upon one side of the furnace, and into a pipe of the next pair on the opposite side of the furnace; means for forcing air under pressure into the other pipe of each pair; and an air blast pipe opening into the furnace at an angle to the axes of said pairs of pipes.
